M. GOLDNER.
PLUNGER OILER FOR WATCHES AND CLOCKS.
APPLICATION FILED MAY 8, 1917.
1,250,851.

Patented Dec. 18, 1917.

UNITED STATES PATENT OFFICE.

MYER GOLDNER, OF BIRMINGHAM, ALABAMA.

PLUNGER-OILER FOR WATCHES AND CLOCKS.

1,250,851.

Specification of Letters Patent. Patented Dec. 18, 1917.

Application filed May 8, 1917. Serial No. 167,320.

To all whom it may concern:

Be it known that I, MYER GOLDNER, a citizen of the United States of America, residing at Birmingham, in the county of Jefferson 5 and State of Alabama, have invented certain new and useful Improvements in Plunger-Oilers for Watches and Clocks, of which the following is a specification.

My invention relates to a plunger oiler 10 more particularly adapted for watches and clocks but which may be designed for effective service in oiling any class of machinery.

The object of my invention is to design an oiler which involves a positive force feed 15 of a quantity of oil which is regulated by the extent to which the plunger or ejector is depressed, this plunger or ejector carrying therethrough the oil distributing duct and being adapted to force through said duct the 20 desired amount of oil admitted below the plunger. In the form in which I use my invention a plunger barrel is provided within the oil receptacle and has openings therein to admit oil below the plunger which travels 25 with a close sliding fit therein. The plunger itself is normally pressed outwardly by a spring and is adapted to be retracted in the barrel by a hollow stem having an oil outlet port adjacent to the plunger. Suitable means 30 are provided for preventing the leakage of oil about the stem.

My invention is so designed that in its normal operation there will be no gravity flow of oil but only a plunger force feed of 35 oil in quantities which may be regulated by practice so that only the exact amount of oil required will be discharged.

My invention will be better understood by reference to the accompanying drawings, in 40 which I have illustrated only its preferred embodiment, and in which:—

Figure 1 is a vertical section through a plunger oiler for watches and clocks.

Fig. 2 is an enlarged view of the plunger 45 barrel broken away; and

Fig. 3 is a detail view of the plunger with its oil distributing actuating stem partly broken away.

Similar reference numerals refer to similar parts throughout the drawings.

As illustrated, I show the oiler casing 1 as an elongated tubular body having one end closed and the other end internally threaded at 2. A plunger barrel 3 is adapted to be 55 inserted into the casing 1 having near one end threads 4 adapted to mesh with the

threads 2 in the open end of the barrel and having a flanged shoulder 5 which abuts against the open end of the casing when the barrel is screwed home therein. The barrel 60 is provided with a plunger chamber 6 extending from its open inner end to a point near the threaded portion 4. Two pairs of oil ports enter this plunger chamber, the upper ports 7 being oppositely disposed and 65 arranged near the top of the casing, while the ports 8 are arranged just above the position of the plunger 9 in the chamber when forced to the extreme outer end of the plunger chamber by the action of the coiled 70 spring 10. This coiled spring 10 surrounds a guide pin 11 on the upper end of the plunger 9 and is adapted to be inserted into the barrel through its upper open end which is normally closed by a screw plug 12. Each 75 oil hole 8 is provided with a downwardly tapering notch 13, the purpose of which will be later described.

The plunger 9 fits with a close sliding fit in the chamber 6 of the barrel and has connected to its under end an operating stem 14 having an oil distributing duct 15 extending lengthwise therethrough with an inlet port 16 just under the plunger. This stem makes a close sliding fit in the guide tip 17 85 of the barrel beyond which its outer end projects a substantial distance.

In operation, the barrel is unscrewed from the casing and the latter filled with oil, the barrel has the plunger 9 and spring 90 10 inserted therein and the cap 12 screwed in to hold the parts assembled, after which the barrel itself is screwed in, closing the open end of the casing and the oiler is ready for service. In using the oiler, the 95 operator depresses the stem 14 against the action of the spring 10, forcing the plunger upwardly until its under end passes the notch 13 of the port 8, thereby admitting oil below the plunger. The quantity of oil 100 is determined by the extent to which the plunger moves opposite or past the supply openings 8 and 13. It being obvious that when the bottom end of the notch 13 is barely open an extremely small quantity 105 of oil will enter below the plunger, whereas, when the plunger is raised as far as it may be by the stem, a full charge of oil accumulates below the plunger and is forcibly ejected thereby through the port 16 and 110 duct 15 and discharged through the end of the stem 14 at the point desired for applica-

tion. An experienced operator can easily acquire a skilled use of the oiler so that the exact minimum requirements of oil can be supplied to the delicate bearings of a watch or clock.

Obviously the oiler may be enlarged and adapted for applying oil to various classes of machinery.

Having thus described my invention, what I claim as new and desire to secure by Letters Patent, is:—

1. A force feed oiler comprising an oil container, a plunger barrel therein, a plunger movable in the barrel, and a tubular stem carried by the plunger and having an oil inlet port below the plunger, there being means to admit oil below the plunger into the barrel.

2. A force feed oiler comprising an oil container, a plunger barrel therein, a plunger movable in the barrel, a tubular stem carried by the plunger and having an oil inlet port adjacent to the plunger, there be-

ing means to admit oil below the plunger in the barrel, and means to prevent the leakage of oil about the stem.

3. An oiler of the character described comprising a casing having an open end, a barrel in the casing having oil ports entering a plunger chamber therein, a plunger making a tight sliding fit in the chamber, a stem projecting with a tight fit through the outer end of the barrel and connected at its inner end to the plunger, there being an oil duct leading lengthwise through said stem and opening through the side thereof near the plunger, and spring means to force the plunger so as to cause the stem to project from the barrel and to close the inner end of the oil duct, substantially as described.

In testimony whereof I affix my signature.

MYER GOLDNER.
